CLAIM

The ornamental design for a novelty fishing machine, substantially as shown and described.

DESCRIPTION

FIG. 1 is a side elevational view of a novelty fishing machine showing our new design;

FIG. 2 is a top plan view thereof;

FIG. 3 is a front elevational view thereof;

FIG. 4 is another side elevational view similar to FIG. 1 but with portions of the wall shown in fragment and the pole and line members in an alternate position;

FIG. 5 is a side elevational view of the opposite side illustrated in FIG. 1; and

FIG. 6 is a rear elevational view.
